CLAIM

The ornamental design for a kitchen faucet, substantially as shown and described.

DESCRIPTION

FIG. 1 is a top perspective view of a kitchen faucet showing our new design;

FIG. 2 is a left side elevational view thereof, the right side being a mirror image of the left side shown;

FIG. 3 is a top plan view thereof;

FIG. 4 is a front elevational view thereof;

FIG. 5 is a rear elevational view thereof; and

FIG. 6 is a bottom plan view thereof.

Fig. 6.

FIG. 4.

FIG. 3.

FIG. 5.
